Patented Aug. 19, 1969

215,021

THERMOMETER HOLDER

Frank R. Beich, Wilmette, and Leonard Seeley, Palatine, Ill., assignors to American Hospital Supply Corporation, Evanston, Ill., a corporation of Illinois

Original design application May 2, 1967, Ser. No. 6,917.
Divided and this application May 2, 1968, Ser. No. 12,193

Term of patent 14 years

Int. Cl. D10—09

U.S. Cl. D52—7

Fig. 3.

Fig. 4.

FIG. 1 is a perspective view of a thermometer holder, showing our new design;

FIG. 2 is a side elevational view;

FIG. 3 is an end elevational view;

FIG. 4 is an elevational view showing the opposite end;

FIG. 5 is a top plan view.

This application is a division of our copending application Ser. No. D. 6,917, filed May 2, 1967.

We claim:

The ornamental design for a thermometer holder, substantially as shown and described.
